UNITED STATES PATENT OFFICE.

MAURICE McQUAID, OF WAUKESHA, WISCONSIN, ASSIGNOR TO AMERICAN CHEST COMPANY, OF WAUKESHA, WISCONSIN, A CORPORATION OF WISCONSIN.

DESIGN FOR A RADIOCABINET.

Application filed April 21, 1926. Serial No. 17,859. Term of patent 3½ years.

To all whom it may concern:

Be it known that I, MAURICE McQUAID, a citizen of the United States, residing in Waukesha, in the county of Waukesha and State of Wisconsin, have invented a new, original, and ornamental Design for Radiocabinets, of which the following is a specification, reference being had to the accompanying drawing, forming part thereof.

In the drawing

Fig. 1 is a perspective view of the radio-cabinet of this invention, and

Fig. 2 is a plan view thereof.

I claim:

The ornamental design for a radiocabinet as shown.

MAURICE McQUAID.
